(57) **CLAIM**

The ornamental design for a companion robot as shown and described.

DESCRIPTION

1.1 : Perspective

1.2 : Front

1.3 : Rear view

1.4 : Top

1.5 : Bottom

1.6 : Right-side view

1.7 : Perspective view showing a state of use 1

1.8 : Perspective view showing a state of use 2

This article is a companion robot for communicating with human beings; the left side view is omitted because it is a mirror image of the right-side view; the shading expressed in the reproductions is for indicating a three-dimensional surface shape of the article.
